Primary Examiner — Robert M Spear*Assistant Examiner* — Marissa J Cash(74) *Attorney, Agent, or Firm* — Sterne, Kessler,
Goldstein & Fox P.L.L.C.(57) **CLAIM**

The ornamental design of an unmanned aerial vehicle, as shown and described.

DESCRIPTION

FIG. 1 is a perspective view of an unmanned aerial vehicle showing our design.

FIG. 2 is a front elevational view of the unmanned aerial vehicle of FIG. 1.

FIG. 3 is a rear elevational view of the unmanned aerial vehicle of FIG. 1.

FIG. 4 is a left-side elevational view of the unmanned aerial vehicle of FIG. 1.

FIG. 5 is a right-side elevational view of the unmanned aerial vehicle of FIG. 1;

FIG. 6 is a top plan view of the unmanned aerial vehicle of FIG. 1; and,

FIG. 7 is a bottom plan view of the unmanned aerial vehicle of FIG. 1.

The broken lines in the figures show portions of the unmanned aerial vehicle that form no part of the claimed design.
